UNITED STATES PATENT OFFICE

2,117,540

STORM SASH OPERATING MEANS

Herman H. Brugmann, Spencer, Iowa

Application October 25, 1937, Serial No. 170,874

12 Claims. (Cl. 20—55)

One object of my invention is to provide an operating means for storm sashes and the like which is simple, durable and comparatively inexpensive to manufacture.

5 A further object is to provide an operating means for storm sashes which, through movement of the upper sash, accomplishes the result of unlocking and opening the storm sash when the upper sash is opened to admit air for ventilation, the operating means effecting closing and locking of the storm sash when the upper sash is moved from open to closed position.

10 A further object is to provide articles of hardware to serve as an inter-connection between a storm sash and the upper sash of a double hung window whereby the sliding operation of the upper sash opens and closes the storm sash.

15 Still a further object is to provide such articles of hardware especially designed so that they may be easily and quickly attached by a carpenter to the usual double hung window and storm sash to thereafter effect operation of the storm sash by movement of the window.

20 Still a further object is to provide hardware including pivoting means for the lower end of the storm sash, lock means for the upper end thereof and operating means for the central portion thereof, the pivoting means being associated with the sill of a double hung window and the lock means and operating means being associated with the upper portion and lower rail respectively of the upper sash of the window.

25 With these and other objects in view, my storm sash operating means consists in the construction, arrangement and combination of the various parts thereof, whereby the objects contemplated are attained, as hereinafter more fully set forth, pointed out in my claims and illustrated in the accompanying drawing, in which:

30 Figure 1 is a vertical sectional view through a window showing my storm sash operating means associated therewith and the storm sash and upper sash closed.

35 Figure 2 is a similar sectional view of a portion thereof showing the parts in a different position with the upper sash slightly lowered.

40 Figure 3 is a similar sectional view showing the parts in still a different position, the upper sash being further lowered and the storm sash being open.

45 Figure 4 is an enlarged sectional view on the line 4—4 of Figure 1 showing an inside elevation of a portion of the hardware I use.

50 Figure 5 is a perspective view of one of the elements of the hardware shown in Figure 4; and

Figure 6 is an enlarged sectional view on the line 6—6 of Figure 1 showing another portion of the hardware which I use.

On the accompanying drawing I have used the reference numeral 10 to indicate the sill of a window. The head jamb thereof is indicated at 11 and the side jamb at 12. In the window frame, upper and lower sashes US and LS are slidably mounted.

5 A storm sash SS is mounted in the window frame. The three sashes thus far referred to are of standard construction. For pivoting the storm sash SS relative to the sill 10, I provide a pin 13 driven into the lower edge of the storm sash, the pin projects into a socket 14 formed in the sill 10. 10 Coacting brackets 15 and 16 are mounted on the storm sash and blind stop 17 of the window frame respectively adjacent the pin 13. In a narrow storm sash one of the pins 13 is sufficient, while in a wider sash two or more of the pins may be 15 used. A pair of the brackets 15 and 16 are provided at each side of the window frame although the drawing shows only one side of the frame.

15 In applying the brackets 15 and 16 to the storm sash and window frame, the brackets 15 are first 20 secured to the lower rail of the storm sash adjacent the bottom corners thereof as shown in Figures 1 and 6. The brackets 15, it will be noted, have flanges 15a terminating in hooks 15b. The brackets 16 have hook fingers 16a adapted to fit 25 over the flanges 15a after the brackets 15 are mounted in position and the storm sash is mounted in the window and closed. The brackets 16 are attached to the blind stop 17 in position to 30 confine the flanges 15a without, however, binding 35 against them and the hooks 15b serve as stops in an excessively open position of the storm sash which position, however, is not assumed during normal operation.

35 Coacting lock elements 18 and 19 are provided 40 on the storm sash and upper sash respectively. These have inclined arms normally engaged with each other as shown in Figure 1. In a window installation there is a pair of them for each stile of the upper sash or one pair for each side of the 45 storm sash SS to insure a substantial lock therefor.

45 A housing 20 is provided which may be countersunk in the stile of the storm sash as shown in Figures 1 and 4 or designed so that it can be 50 mounted on the surface thereof if desired. The housing 20 is provided with a cover plate 21. The housing and cover are secured in position by screws 22. Within the housing 20, a plate 23 is provided. It is channel-shaped and the flanges 55

24 thereof are pivotally mounted on a pin 25 extending from side to side of the housing 20. The plate 23 is biased to the position shown in Figure 1 by a spring 26.

5 On the lower rail of the upper sash I mount a pair of angle brackets 27 and 28. These pivotally support the upper end of a link L. The link L as shown in Figure 5 may be formed of flat bar stock. The link L is twisted as indicated at 10 29 and terminates in a T-head 30 bent at right angles to the general plane of the link. Adjacent the T-head, the link is provided with a pair of notches 31 which makes this portion of the link less in width than the width of a slot 32 formed 15 in the cover plate 21 of the housing 20. The T-head 30 is arranged inside the cover plate and thus I provide a sliding, but non-disengageable connection between the link L and the storm sash SS. The link L is screw-threaded as indicated 20 at 33 to receive a set screw 34. A lock nut 35 is positioned on the set screw 34.

Practical operation

In the operation of my device, after the hardware is installed on the window and its storm sash, the parts are normally in the position of Figure 1 when the window is closed. The upper sash US may be lowered which initially unlocks the storm sash by separating the lock element 19 25 from the lock element 18 as shown in Figure 2. During the lowering of the upper sash, the T-head 30 of the link L slides along the plate 23 causing it to pivot on the pin 25 against the action of the spring 26. Slightly lower than the 30 position shown in Figure 2, the T-head 30 will engage the bottom wall of the housing 20 and since the link L is extending at an angle to the vertical, any further lowering of the upper sash will tend to swing the storm sash outward.

As the upper sash is thereafter lowered to a 40 further degree, for instance, as shown in Figure 3, the storm sash will be swung further open so that ventilation is provided through the opened storm sash and the upper open sash. If additional ventilation is desired, the lower sash can 45 also be opened.

Due to the spring 26 urging the plate 23 to the 50 position shown in Figure 1, after the T-head 30 passes the lower end of the plate during the lowering operation, the T-head will hook under the edge of the plate as shown in Figure 3. Accordingly when the upper sash is subsequently raised the link L will pull inwardly on the storm sash and just prior to the position of Figure 2 being assumed, the set screw 34 will engage the plate 55 23 to swing it to a position where the T-head 30 will unhook from it. This arrangement thereby permits further sliding of the sash for the purpose of locking the storm sash in closed position as the T-head 30 can then slide vertically in the slot 32 without pulling up on the storm sash due to being hooked under the lower edge of the plate 23.

The set screw 34 is made adjustable so that 60 proper unhooking of the T-head 30 is effected during the raising of the upper sash. The lock nut 35 retains the set screw in properly adjusted position.

The type of hardware which I have provided 70 at the center of the storm sash, permits movement of the upper sash for locking and unlocking purposes without effecting swinging movement of the storm sash. During the closing of the storm sash, it is necessary to first swing it inwardly and then lock it by the final closing of

the upper sash. For this reason a simple lost motion connection between the upper sash and the storm sash will not suffice and I therefore provide the type of hardware disclosed at the center of the storm sash to accomplish the desired 5 results. Thus I am able to use the upper sash as a means to lock and unlock the storm sash as well as swing it to opened and closed positions.

Some changes may be made in the construction and arrangement of the parts of my storm 10 sash operating means without departing from the real spirit and purpose of my invention, and it is my intention to cover by my claims, any modified forms of structure or use of mechanical equivalents, which may be reasonably included 15 within their scope.

I claim as my invention:

1. In a storm sash operating means for double hung windows, an elongated element connected with a storm sash intermediate the top and bottom thereof, a link slidably connected therewith and pivotally connected with the lower rail of the upper sash of the window, locking elements connected with said storm sash and said upper sash and engageable with each other adjacent 25 raised position of the upper sash and means for pivoting the lower end of the storm sash to the window frame.

2. In a storm sash operating means for double hung windows, an element connected with a storm 30 sash intermediate the top and bottom thereof, a link connected with the lower rail of the upper sash of the window, and having a lost-motion connection with said element, locking elements connected with said storm sash and said upper sash 35 and engageable with each other adjacent raised position of the upper sash and means for pivoting the lower end of the storm sash to the window frame.

3. In a storm sash operating means for double 40 hung windows, an element connected with a storm sash intermediate the top and bottom thereof, a link connected with the lower rail of the upper sash of the window, and having a lost motion connection with said element, locking elements connected with said storm sash and said upper sash 45 and engageable with each other adjacent raised position of the upper sash, means for pivoting the lower end of the storm sash to the window frame, a pivoted plate supported adjacent said 50 first mentioned element, said link having a hook end to engage one end of said plate during the lowering and raising of the upper sash.

~ 4. In a storm sash operating means for double hung windows, an elongated element connected 55 with a storm sash intermediate the top and bottom thereof, a link slidably connected therewith and pivotally connected with the lower rail of the upper sash of the window, locking elements connected with said storm sash and said upper sash and engageable with each other adjacent 60 raised position of the upper sash, means for pivoting the lower end of the sash to the window frame, a pivoted element supported adjacent said elongated element, said link having a hook end to engage one end thereof during the lowering and raising of the sash, and a projection on 65 said link to engage said pivoted element and swing it to position for unhooking said hook end therefrom during raising of the upper sash.

5. In a storm sash operating means for double 70 hung windows, an elongated element connected with a storm sash intermediate the top and bottom thereof, a link slidably connected therewith and pivotally connected with the lower rail of 75

the upper sash of the window, locking elements connected with said storm sash and said upper sash and engageable with each other adjacent raised position of the upper sash, means for pivoting the lower end of the storm sash to the window frame, said lock elements being inclined relative to the vertical to urge said storm sash toward closed position during the final closing of the upper sash.

10. 6. In a storm sash operating means for double hung windows, an elongated element connected with a storm sash intermediate the top and bottom thereof, a link slidably connected therewith and pivotally connected with the lower rail 15 of the upper sash of the window, locking elements connected with said storm sash and said upper sash and engageable with each other adjacent raised position of the upper sash and means for pivoting the lower end of the storm 20 sash to the window frame, said means including pin connections between the bottom of the storm sash and the window sill.

7. In a storm sash operating means for double hung windows, an elongated element connected 25 with a storm sash intermediate the top and bottom thereof, a link slidably connected therewith and pivotally connected with the upper sash of the window, locking elements connected with said storm sash and said upper sash and engageable 30 with each other adjacent raised position of the upper sash, means for pivoting the lower end of the storm sash to the window frame, said means including pin connections between the bottom of the storm sash and the window sill, and brackets 35 on the storm sash and window frame and coacting with each other to prevent dislocation of the pin connections from the storm sash and window sill.

8. In a storm sash operating means for double 40 hung windows, means for pivoting the storm sash to the window frame, a housing connected with said storm sash and having a vertical slot therein, a link connected with the upper sash of the window and having a T-head slid able in said slot, 45 and lock elements on said upper sash and storm sash to coact with each other in the closed position of the upper sash.

9. In a storm sash operating means for double hung windows, means for pivoting the storm sash 50 to the window frame, a housing connected with

said storm sash and having a vertical slot therein, a link connected with the upper sash of the window and having a T-head slid able in said slot, lock elements on said upper sash and storm sash to coact with each other in the closed position of the upper sash and a pivoted element supported in said housing, said link having a hook end to engage the lower end thereof during lowering and raising of the upper sash.

10. In a storm sash operating means for double 10 hung windows, means for pivoting the storm sash to the window frame, a housing connected with said storm sash and having a vertical slot therein, a link connected with the upper sash of the window and having a T-head slid able in said 15 slot, lock elements on said upper sash and storm sash to coact with each other in the closed position of the upper sash, a pivoted element supported in said housing, said link having a hook end to engage the lower end thereof during lowering and raising of the upper sash and means 20 projecting from said link to engage said pivoted element and swing it to position for unhooking said hook end therefrom during raising of the upper sash.

11. In a storm sash operating means for double hung windows, means for pivoting the storm sash to the window frame, a lost motion connection between said storm sash and the upper sash of the window, said lost motion connection including a pivoted element, a hook element to engage therewith and a projection on the hook element to disengage it from the pivoted element during the raising of the upper sash and closing of the 30 storm sash.

12. In a storm sash operating means for double hung windows, means for pivoting the storm sash to the window frame, a housing connected with said storm sash and having a vertical slot therein, a link connected with the upper sash of the 40 window and having a T-head slid able in said slot, a pivoted element supported in said housing, said link having a hook end to engage the lower end thereof during lowering and raising of the upper sash and means projecting from 45 said link to engage said pivoted element and swing it to position for unhooking said hook end therefrom during raising of the upper sash.

HERMAN H. BRUGMANN. 50
